Fig. 3

Fig. 4

Fig. 5

FIGURE 1 is an isometric view of a combined cover and foot guard for a treadle electric switch unit incorporating my new design;

FIG. 2 is a side elevational view thereof;

FIG. 3 is a front end view thereof;

FIG. 4 is a top view thereof; and

FIG. 5 is a rear end view thereof.

The dominant features of my new design reside in the portions shown in solid black lines in the drawings.

The broken line showing of an electric switch unit is for illustrative purpose only.

I claim:

The ornamental design for a combined cover and foot guard for treadle electric switch unit, substantially as shown and described.
